UNITED STATES PATENT OFFICE.

WILLIAM W. ALEXANDER AND EDWARD T. KEIM, OF DENVER, COLORADO; SAID KEIM, ADMINISTRATOR OF SAID ALEXANDER, DECEASED, ASSIGNOR, BY MESNE ASSIGNMENTS, TO THE PROTECTIVE SIGNAL MANUFACTURING COMPANY, A CORPORATION OF COLORADO.

SYSTEM AND APPARATUS FOR RECORDING ELECTRIC SIGNALS.

1,050,780.

Specification of Letters Patent. Patented Jan. 21, 1913.

Application filed April 19, 1911. Serial No. 622,017.

To all whom it may concern:

Be it known that we, WILLIAM W. ALEXANDER and EDWARD T. KEIM, citizens of the United States of America, residing at Denver, in the county of Denver and State of Colorado, have invented certain new and useful Improvements in Systems and Apparatus for Recording Electric Signals, of which the following is a specification.

10. Our invention relates to a system and apparatus for recording electrically transmitted signals and more particularly to the receiving instruments of telegraphic systems in which the transmitting instruments are of a character to transmit the respective numbers of the stations at which they are installed by an intermittent opening or closing of the electric circuit in which they are connected.
15. The principal object of the present invention resides in the provision of an electro-mechanical instrument of simple construction by which different signals or messages sent from a number of stations in a system 20. of telegraphy, are automatically recorded upon a sheet of paper or other suitable material together with the time of day at which they were individually received. The receiving instrument is to this end 25. composed essentially, of a time controlled mechanism which moves a drum upon which a continuous record-sheet is wound at a uniform rate of speed, a device adapted to intelligently record electric signals or 30. messages upon the said sheet, preferably by marks which are spaced in accordance with the intervals between the electric impulses intermittently produced by action of the transmitting instrument, and a time 35. recording device which is automatically actuated at regular intervals of predetermined duration, to produce upon the same sheet a series of equidistant impressions for the purpose of establishing for future 40. reference the time of day at which the recorded signals or messages were individually received.

In extensive telegraphic systems of the character to which our invention more particularly appertains, a plurality of transmitting instruments are connected in one

circuit with the central receiving instrument at different points of the line, and as it would be impractical to place all the stations of an extensive system in one circuit, 55 a number of circuits are provided, all of which may be connected with one common source of electricity.

For the purpose of simplifying the construction of the receiving instrument as 60 well as to reduce the amount of work required in examining, translating or copying the records, or in filing them for future reference, we combine in systems of the above description, in one instrument, a plurality of aligned signal recording units connected respectively in the several circuits in association with one record-sheet which moves transversely to the line of units, and with one or two time recording devices 70 placed at the ends of the series of units so that all the impressions produced by the latter will be assembled upon the one sheet together with equidistant marginal impressions, which by their positions relative to 75 the signal-records, determine at what hours or fractions thereof, they were received.

In more extensive telegraphic systems the signal recording units may be divided into two or more series which, while assembled 80 in one instrument, record the signals of their respective units upon separate sheets of paper which, however, are moved by one common time-controlled mechanism.

In the accompanying drawings an instrument is represented in which two series of signal-recording devices each composed of thirteen units, are assembled to record the signals transmitted through their respective circuits upon two continuous sheets of 90 paper which are moved longitudinally transverse to the alignment of the units by one common time-controlled mechanism which also serves to actuate the time recording contrivances of which there are two for 95 each of the above mentioned series.

The several signal recording devices comprised in one receiving instrument are identical in construction and operate independently from each other and inasmuch as the 100 construction of the said device involves an invention separate from the present one it

has been made the subject of another application for patent.

In the drawings, in the various views of which like parts are similarly designated, 5 Figure 1, represents a plan view of the entire instrument as outlined above, Fig. 2, a front elevation of the same, Fig. 3, a vertical section taken along the line 3—3 Fig. 1, Fig. 4, a similar section taken along the 10 line 4—4, Fig. 2, Fig. 5, a fragmentary view of the clock-controlled electro-magnetic mechanism which moves the record sheet, Fig. 6, a fragmentary view of the clock-movement by which the mechanism of 15 the preceding figure, is actuated, Fig. 7, a fragmentary view of the continuous sheet of paper upon which the electric signals and the time at which they are received, are recorded. Fig. 8, a diagrammatic view of 20 the electrical connections included in the telegraphic system at the receiving end of of which the recording instrument is installed, Fig. 9, a side elevation of one of the devices by which the signals are recorded upon the 25 sheet shown in Fig. 7. Fig. 10, an enlarged view of the part of the said device which carries the stylus by means of which the impressions are produced, Fig. 11, a horizontal section taken along the line 11—11, Fig. 9, Fig. 12, a similar section along the line 12—12 Fig. 9. Fig. 13, a perspective view of the bell crank-lever included in the construction of the device shown in Fig. 9, Fig. 14, a side elevation of one of the contrivances 30 designed to designate by impressions upon the marginal portions of the sheets shown in Fig. 7, the time at which the various signals are recorded, Fig. 15, a section taken along the line 15—15, Fig. 14, Fig. 40 16, an enlarged plan view of the part of the device shown in Fig. 14, which carries the stylus by means of which the impressions are produced, Fig. 17, an elevation of the mechanism of a transmitting instrument 45 of the character employed in telegraphic systems of the class to which the present invention, particularly appertains, Figs. 18, 19, 20 and 21 enlarged sectional views taken along the line 18—18, Fig. 9, respectively 50 illustrating the positions successively assumed by the stylus in recording a signal sent to the device shown in Fig. 9, and, Figs. 22, 23, 24 and 25 similar views taken along the line 22—22, Fig. 14, to illustrate 55 the successive positions of the stylus comprised in the time-recording contrivance, while an impression is being produced thereby upon the sheet shown in Fig. 7.

Referring to the drawings by numerical 60 reference characters, the numeral 2 designates the skeleton frame upon which the various operating parts of the instrument are assembled and which is preferably inclosed in a casing, which for obvious reasons has been omitted from the drawings.

The signal recording units, which as hereinbefore explained, are arranged in two groups, are designated by the numeral 3, while the devices which are disposed at opposite ends of the said series to periodically record recurrent points of time, are indicated by the character 4.

The continuous sheets of paper or other suitable material upon which the records are made, and designated in the drawings, by the numeral 5, are wound upon spools 6 which are rotatably mounted at the lower portion of the frame 2. The sheets 5 are led from the respective spools through the medium of parallel guide rollers 7, over 75 horizontally disposed anvil plates 8 which provide striking surfaces for the styls of the several recording devices which are alined transversely to the direction in which the sheets are moved, and the ends of the 80 sheets are secured by means of clamps 9, to winding drums 10 which in the operation of the instrument, are rotated by the clock controlled mechanism hereinabove referred to.

When two groups of recording units are 90 assembled in one instrument, as in the construction shown in the drawings, the drums 10 are connected to rotate in unison in opposite directions by means of gear-wheels 12, and it will be understood that the sheets 95 5 are of sufficient width to receive the impressions of all the recording devices comprised in each of the respective series.

For the purpose of clearer illustration the record-sheets 5 have been represented in the 100 various elevations and sectional views of the drawings by means of heavy dash-dot lines.

The time-controlled feeding mechanism above referred to, consists of an electro-magnet 13, the windings of which are located in an electric circuit with a resilient contact blade 14 and a therewith engaging contact-point 15 both of which are secured in operative proximity to the pendulum 16 of a clock movement 17 of ordinary construction, such as is shown in Fig. 6. The pendulum 16 carries a curved piece 18 which during each oscillation thereof temporarily separates the contact point 15 from the blade 14 with which it is, normally, in engagement, with the result that while the clock movement is in action, the magnet 13 is periodically energized.

The armature 19 of the electro-magnet is connected with a lever 20 which is fulcrumed upon a post 21 and which is attached at one of its ends to the retracting spring 22 which normally maintains the armature in the position in which it is separated from the core of the magnetic coil. A 120 spring-controlled pawl 23 pivotally mounted at the opposite end of the lever 20, is disposed to engage during the movement of the armature 19 toward the magnet, with the teeth of a ratchet-wheel 24 and to move 125 115 110 105 100 95 90 85 80 75 70 65 60 55 50 45 40 35 30 25 20 15 10 5 0

the same about its axis of rotation until arrested by contact with an adjustable stop 25. When the attractive force of the magnet ceases, the retracting spring 22 and the spring 26 which acts directly upon the pawl, return the latter to its original position which is shown in full lines in Fig. 5 of the drawings, and it will thus be seen that during the uniform oscillatory movement of the pendulum 16 of the clock movement the ratchet-wheel is intermittently rotated at equal intervals and through arcs of equal length the extent of which may be varied by adjustment of the stop 25.

15 A spring pawl 27 which constantly engages the teeth of the wheel 24, is provided to prevent retrograde movement of the same, while an adjustable stop 28 limits the upward movement of the lever 20. The intermittent rotary motion of the ratchet wheel 24, is by means of a pinion 29 secured upon its spindle transmitted to a gear-wheel 30 which is mounted upon the frame 2 and the movement of the last mentioned wheel 25 is by means of a therewith concentric pinion 31 imparted to one of the gear-wheels 12 which as hereinbefore explained, are connected with the winding drums 10.

It will be understood from the above description that through the instrumentality of the gear train, the sheets 5 are wound upon the respective drums 10 at a rate of speed which is regulated by the movement of the clock and that in consequence, during 35 each hour or other space of time, portions of the said sheets will travel over the respective anvil plates 8. Periodically recurring points of time such as the hour, the half-hour, or the quarter hour are at corresponding intervals recorded upon the marginal portions of the sheets 5 by the time-recording contrivances 4 which are disposed at opposite ends of each series of signal-recording units 3, and which are operatively associated with the same clock which actuates the winding-drums 10. In the construction shown in the drawings, this association is established through the medium of the striking gear train 17 which periodically actuates the lever 33 of the hammer 50 which ordinarily strikes upon a gong or spring to audibly announce the hours of the day.

A contact 34 secured upon the clock-frame in the path of the lever 33, constitutes a terminal of a normally open circuit in which the lever is connected through the medium of the metallic parts of the clock and the time-recording devices 3 each including an electromagnet 35, the coil of which is located in the said circuit. When at the end of each hour, or aliquot part thereof, the striking gear of the clock-movement is released to impart to the lever 33 a succession of oscillatory movements in accordance

with the number of the hour at which the action takes place, the armatures of the various magnets 35 are as many times attracted to the cores thereof by the intermittent closing of the circuit by contact of the lever 70 with the terminal 34, and this series of movements of each armature is transmitted to a therewith associated stylus which is disposed to engage the sheet 5 as will now be described.

Each of the time-recording devices comprises an oscillatory frame 75 which is mounted to move about a vertical axis between two horizontal plates 44 and 45 on the supporting structure 2 which serve to support the various recording instruments comprised in each series. The oscillatory element 75 consists of an upright rod 78, the ends of which are journaled in openings in the respective plates and upon which are secured two transverse bars 75 and 77 the lower one of which supports the electromagnet 35. The two bars are connected at their rear ends by a poise 80 and a second poise 81 is carried at the opposite end of 85 the upper bar for the purpose of retarding the movement of the frame about its axis of oscillation by their inertial tendency to remain in a state of rest. A coiled spring 79 which surrounds the portion of 90 the spindle 78 above the upper bar, is connected at its opposite ends respectively to the latter and to the top-plate 44, to yieldingly oppose a movement of the frame 75 about its axis, from its normal position of 95 rest.

The armature 83 of the magnet 35 is connected with a plate 84 which has an articulate connection with a block 85 on the rod 78 and which is held in its normal position 100 by means of a retracting spring 86 disposed between the plate 84 and the upper transverse bar 76 of the frame 75. Projecting forwardly from the armature 83, is the stylus-arm 87 which is preferably composed 105 of two convergent members which are connected at their outer extremities. One of these members carries two bearing blocks 90 which are adjustably secured by set-screws 91, and which serve to support a shaft 89 110 upon which the downwardly projecting stylus 88 is rotatably mounted. A spring 92 coiled around the shaft 89 tends to maintain the stylus in its normal position in which it slants slightly from the perpendicular in 115 engagement with a stop 93 on the adjacent block 90 (see Fig. 22) and a second stop 94 secured to the upper bar 76 of the frame is provided to limit the upward movement of the arm 87. The magnet 35 being in a circuit with the contact 34 and the lever 33 of the striking movement of the clock as hereinbefore explained, attracts its armature each time the said lever is actuated to strike the hour, or the half or quarter hour as 120 125 130

the case may be, and during each movement of the armature, the point of the stylus 88 is brought in engagement with the portion of the sheet 5, disposed upon the plate 8, which in consequence is punctured. When the point of the stylus enters the surface of the record sheet, the armature 83 has not yet completed its downward movement with the result that during continuation of the said movement the stylus after having engaged the sheet, will be deflected about its axis of rotation and against the action of the spring 92 as is shown in Fig. 23.

Inasmuch as the sharp point of the stylus 15 is held against displacement in the perforation produced in the sheet 5, it follows that its point of connection with the arm 87 must move laterally with relation to the perpendicular passing through its point of contact 20 with the sheet or with other words, that the oscillatory frame is compelled to move about its axis until the circuit of the magnet is broken when the arm will move upwardly impelled by the action of the spring 86 while 25 the frame is momentarily held in its adjusted position by the inertia of the poises 80 and 81, (see Fig. 24). Before the spring 79 has had time to overcome this inertial tendency, the magnet is again energized by 30 the engagement of the arm 33 of the clock-movement with the stop 34, during its second stroke with the result that the stylus 88, which, during the upward motion of the arm 87 had been returned to its original 35 position by the spring 92, will again engage the sheet 5, but this time at a point spaced from the puncture previously produced. During the continued movement of the armature toward the core of the magnet 40 after the point of the stylus has entered the sheet, the stylus is again deflected as hereinbefore explained and when during subsequent upward movement of the arm 87 in the period intervening between two movements 45 of the lever 33, the stylus is again returned to its normal position, the frame has again moved laterally a distance similar to that of its previous movement, so that when by subsequent energization of the magnet 50 the armature is again attracted, the point of the stylus will engage the sheet at a point spaced from the second puncture, (see Fig. 25), and this operation will be repeated until the lever 33 has completed its succession 55 of movements in accordance with the number of the hour, when the striking movement is again locked, and the spring 79, during continued inaction of the magnet, overcomes the inertia of the poises and returns 60 the frame 75 to its original position.

As a result of the above described operation the sheet has received a plurality of punctures equidistantly spaced along a line transverse to the line in which the paper is 65 moved by the feeding mechanism and corre-

sponding in number with that of the hour at which the action took place and inasmuch as the winding drum upon which the sheet is wound is rotated at a uniform rate of speed by the clock-movement, it will be seen that 70 at the expiration of a certain space of time, the sheet will bear a series of substantially equidistant impressions which individually indicate the successive hours of the day at which they were produced. 75

To prevent the possibility of forming a faulty record by the stylus striking beyond the edge of the sheet in case the latter becomes laterally displaced, two time recording instruments are placed at opposite ends 80 of each series of signal recording units and arranged so that their stylus arms move laterally in the same direction.

A portion of the record sheet as it appears after the instrument has been in action for about one hour has been illustrated in Fig. 7 of the drawings in which the numerals 93 indicate the marginal impressions made by the time-recording devices and 94 those produced by the signal recording units 90 as will hereinafter be described. The portion between the two successive time records 93, made respectively at the hours of four and five, represents, of course, the distance the sheet traveled during one hour of time, 95 and as the movement of the paper is at all times uniform and in accordance with that of the clock-mechanism, the exact time at which a signal record is made on the sheet, may be accurately established by ruling the 100 sheet transversely in accordance with aliquot divisions of the hour, either before or after it is placed in the instrument. In the example shown in the drawings, the spaces between these equidistant lines, designated by 105 the numerals 95, each indicate five minutes of time and in addition to the transverse lines, lines 96 ruled parallel to the longitudinal edges of the sheet are provided to separate the records made by the different signal-recording units comprised in the series. By placing the numbers of the electric circuits with which the units are respectively connected, at the top of the longitudinal columns, as is shown in the drawing, the 110 sheet after it has been detached from the main portion wound upon the spools of the instrument and properly dated, may be used at any future time to indicate the exact time at which a signal was transmitted from a 115 given station over a given circuit. 120

While the construction of the instruments by which the electric signals are transmitted to the receiving instrument does not form part of the present invention, I have shown 125 in Fig. 17 of the drawings, the mechanism of one of the call-boxes 100 of a local telegraphic system, an explanation of which will aid to a great extent, in conveying a clear understanding of the operation of the 130

signal recording devices which will herein-after be described. Each of the call boxes above referred to is designed to transmit a predetermined number to the receiving instrument of the system, each time it is actuated, by a succession of electric impulses which are produced by the alternate closing and opening of the normally closed line-circuit in which said boxes are included. The 10 number of impulses transmitted each time the mechanism of the box is actuated equals the sum of the units contained in the several numerals of which the number to be transmitted, is composed and the respective 15 values of these numerals are recorded or announced at the receiving end of the system by increasing the length of the intervals between the last and first impulses of the numbers which correspond with the quantities of the units contained in two successive numerals, over the uniform periods intervening between the successive impulses which collectively represent the individual value of each numeral.

25 In the construction shown in Fig. 17, the above described result is obtained by means of a rotary disk 36 which is actuated by a spring when the normally blocked gear train 37, associated therewith, is released by manipulation of an operating handle 38. The disk has a plurality of peripheral notches 39 which are arranged in groups, separated by enlarged spaces, in accordance with the numerals contained in the number to be transmitted. In the example shown, this number is 218 and the spaces between the first two notches and the third one, and between the latter and the following group of eight notches are accordingly made larger than 40 those between the notches comprised in each group. The peripheral edge of the disk 36 is normally engaged by the end of a resilient brush 40, which is adapted to enter each of the notches 39 during the rotary movement 45 of the disk without coming in contact with the latter, and the disk and the brush are connected respectively at opposite ends of a break in the normally closed line-circuit. Each signal-recording unit 3, has an electro- 50 magnet 41 the windings of which are included in the normally open local circuit which through a relay 42 shown in the dia- 55 grammatic representation in Fig. 8 of the drawings, is electrically connected with the line circuit in which the transmitting instruments are disposed so that the electric impulses caused by actuation of the latter, will excite the magnet 41 at intervals corresponding in length with the spaces between 60 the notches 39 in the disk 36.

The electro-magnets 41 of the signal recording instruments are like that of the hereinbefore described time recording device, each secured upon an oscillatory frame 65 43 which is mounted to move about a verti-

cal axis between the plates 44 and 45 on the frame 2. The oscillatory element 43 consists of a spindle 46 the ends of which are journaled in openings in the plates, 44 and 45 and upon which are secured two transverse bars 47 and 48, the lower one of which supports the electro-magnet 41. The two bars are connected at their rear ends by a poise 49 and the opposite end of the upper bar carries a second poise 50 for the purpose 70 hereinbefore described. A coiled spring 51 is connected at its opposite ends respectively to the upper bar 47 and to the top-plate 44 to yieldingly oppose a movement of the frame 43 about its axis, and the armature 52 of the magnet 41 is connected with a plate 53 which has an articulate connection with a block 54 on the rod 46, and which is held in its normal position by means of a retracting spring 55, disposed between the plate 53 and the upper transverse bar 47 of the frame 43. Projecting forwardly from the armature plate 53, is the stylus-arm 56, formed, similar to that of the time-recording instrument, of two converging members which at their connected forward ends carry the stylus 44 which, by means of a nut 58 may be longitudinally adjusted to vary the distance of its point from the surface of the anvil plate 8 from which it is, normally, spaced. One of the members of the arm 56 carries two bearing-blocks 59 which are adjustably secured thereto by means of set-screws 60 and which serve to support a shaft 61 upon which a bell crank 95 100 105 110 115 120 125 130 62 is rotatably mounted. The normally upright arm 63, of the bell crank, which is offset from the other laterally projecting arm 64, is sharpened at its upper edge and in the operation of the device, serves as a pawl which by engagement with the teeth of a rack 65 secured to a transverse bar 66 on the frame 2, moves the oscillatory frame 43 intermittently about its axis, as will herein-after be more fully explained. A spring 67 coiled around the shaft 61, is connected with the bell crank 62 and with one of the blocks 59, to resiliently oppose a downward movement of the pawl-arm 63 about its axis.

The normal position of the pawl-arm in which it slants slightly from the perpendicular, is determined by its engagement with the member of the arm 56 to which the blocks 59 are secured, and a stop 68 which is fastened to the upper bar 47 of the oscillatory frame, is disposed to be engaged by the laterally extending arm 64 of the bell-crank for the purpose of disengaging the pawl 63 from the rack when the arm 56 is in its uppermost position, as shown in Fig. 18 of the drawings. The lower bar 48 of the frame, supports in addition to the electromagnet 41, a second magnet 69 of smaller dimensions, whose armature 70 is secured to a plate 71 which is resiliently connected with a sup-

port 72 which by means of standards 73 is rigidly mounted upon the base plate 45. The windings of both the magnets 41 and 69 are connected in the same local circuit as is shown in Fig. 8, and inasmuch as the coil of the magnet 69 is smaller than that of the magnet which controls the movements of the stylus arm 56, it will be energized in a lesser period and thus attract its armature before that of the larger magnet has come in contact with its core. The result is that the oscillatory frame 43 can move about its axis only during the intervals between two successive energizations of the magnets, while, when by the downward movement of the arm 56, the stylus 47 is brought in engagement with the sheet 5, to produce an impression thereon, the frame is locked against movement about its axis by the contact of the armature 70 of the magnet 69 with the core of the same.

When the parts of the signal-recording device, as above described are in their normal position of rest (see Fig. 13) the stylus arm 56 is by the action of the spring 51 held in its highest position with the member 64 of the bell crank 62 in engagement with the stop 68 and the pawl-member 63 slanting free from contact with the teeth of the rack 65, while the oscillatory frame is held yieldingly at one end of the path in which it has its movement, by means of the spring 51 coiled around the upper end of the spindle 46.

When by actuation of the disk 36 of the transmitting instrument shown in Fig. 17, a succession of electric impulses is transmitted through the line circuit to the relay 42 and thence through the local circuit to the two magnets 41 and 69 of the signal recording device, the oscillatory frame 43 is at each impulse, locked against rotation by the engagement of the armature 70 of the small magnet with the core thereof as hereinbefore explained, after which the stylus arm is moved downwardly by the attractive force of the magnet 41, to bring the point of the stylus 47 forcibly in engagement with the portion of the sheet 5, at the time disposed upon the anvil, which, in consequence is punctured. During the downward movement of the stylus arm the member 64 of the bell-crank moved free from engagement with the top 68, with the result that the pawl-member 63 is returned by the spring 67, to its normal position in which it slants slightly from the perpendicular in engagement with the adjacent member of the arm 56, which serves as a stop to limit its movement about its axis, as shown in Fig. 19. Now, when by engagement of the brush 40 in the transmitting instrument, with the peripheral space on the disk 36, between two successive notches 39, the magnets 41 and 69 are momentarily deenergized, the

frame 43 is again free to rotate about its axis of oscillation, and the stylus arm is impelled upwardly by the retracting spring 55. During this movement of the stylus arm, the sharp edge of the substantially upright pawl member 63 of the bell crank 62 is brought in engagement with the teeth of the rack 65 before the other member 64 engages the stop 68, with the result that during the continued upward motion of the arm 56, the pawl member is deflected about its axis of rotation, against the action of the spring 67 and, inasmuch as the sharp edge of the said member is held against displacement in one of the interdental spaces of the rack 65, into which it had entered, it follows that its point of connection with the arm must move laterally with relation to the perpendicular passing through its point of contact with the rack or, in fact, that the oscillatory frame is compelled to move about its axis until by engagement of the crank-member 64 with the stop 68, the pawl member is once more freed from engagement with the teeth of the rack. However, before the arm 56, whose movement together with the frame 43, is retarded by the inertia of the two poises 49 and 50, has had time to complete its upward movement, (see Fig. 20) the magnets are again energized by the impulse transmitted thereto while the end of the brush 40 of the transmitting instrument is in register with the notch of the contact disk 36 next to the peripheral space with which it previously was in contact, with the result that the movement of the frame 43 with the arm 56, is arrested while the pawl is still in engagement with the rack, and is thus held against rotation while the stylus arm is again moved downwardly by the attractive force of the magnet 41, and the stylus is once more brought in engagement with the sheet 5, but this time at a point spaced from the puncture previously made in accordance with the length of the interval between the two impulses, by reason of the lateral movement of the frame in its plane of oscillation during the deflectory movement of the pawl, (see Fig. 21). At the commencement of the next period of deenergization of the magnets, the sharp edge of the pawl is again brought in engagement with the rack at a point perpendicularly above the same while it was in the lower position and before the spring 51 on the frame 43, has had the time to overcome the inertial tendency of the poises to remain in a state of rest, and when, during subsequent deflection of the pawl, the magnets are again excited, the stylus will be brought in contact with the paper at a point spaced from the second puncture in accordance with the length of the interval between the two impulses, and this action will

be repeated until the entire signal is transmitted at which time the sheet 5 has received a series of punctures spaced along a line transverse to the direction of its movement, which correspond in number with the electrical impulses transmitted or with the number of notches in the contact disk of the transmitting instrument.

It will have been observed that the extent of the lateral movement of the arm 56 of the frame 43, during the period intervening between two successive impulses is proportionate to the angle of deflection of the pawl and in consequence to the duration of the said period, so that when the interval between two electric impulses is lengthened the space between the respective punctures in the sheet 5 will be proportionately increased. The result is that the unequal spacing between the notches 39 on the disk 36 will be accurately represented in the record made upon the sheet and that the number transmitted may be read at any time from the sheet by separately adding the number of punctures comprised in each group.

A plate 74 which extends transversely over the sheet in proximity to the line along which it is engaged by the styli of the various recording devices, is provided to arrest upward movement of the sheet with the stylus when the latter is being separated therefrom, and it will be understood that the longitudinal movement of the sheet is so slow in comparison with the rapidity with which the succession of impulses are transmitted and the punctures are produced that the latter will be arranged practically in one straight line transverse to the direction in which the paper is impelled over the anvil-plate 8.

In the diagrammatic view, Fig. 8 of the drawings, two circuits have been shown in connection with a corresponding number of signal-recording units of the receiving instrument and with two time recording devices, the various magnets and contact-members having been indicated by the same reference numerals, employed in the foregoing description. The two normally closed line- or outside-circuits, are represented respectively by light and heavy dash-dot lines, the normally open, local circuits respectively by full and broken lines, the circuit of the time-controlled mechanism by full lines, with the exception of that part which is provided by the metallic frame and operating parts of the clock, and which has been shown in light broken lines. The reference numeral 97 designates the source of electricity of the line-circuits and 98 that of the local-circuits. The hereinbefore referred to relays by which the main and local circuits are electrically connected are designated by the numerals 42, a switch by which if so de-

sired, the clock-circuit may be broken, is designated in Figs. 8 and 1 by the numeral 99 and the transmitting instruments connected in the line circuit are indicated by the reference characters 100.

As the operation of the instrument has been referred to at intervals during the course of the foregoing description, it will only be necessary to outline it briefly at this point. The rolls of paper or other material having been mounted upon the spools 6, in the manner shown in Fig. 2, their ends are drawn over the guide rollers 7 and the upper surfaces of the intermediate anvil-plates 8, and securely fastened to the winding drums 10 by means of the clamps 9. The clock-movement in electrical association with the feeding mechanism, imparts an intermittent movement to the winding drums at a uniform rate of speed, and the time-recording instruments which are actuated by the striking movement of the clock will by the production of a series of equidistant groups of punctures, separately corresponding with the numbers of the hours at which they were made, establish a permanent record of the time at which the signals sent from the transmission instruments were received. Each time one of the transmission instruments is actuated, its number is accurately recorded in the column of the sheet corresponding with the circuit in which it is located, by the spaced groups of punctures which present intelligible representations of the numbers transmitted.

It will thus be observed that the invention provides an entirely automatic instrument for accurately and properly recording all the electric signals and the time at which they were received during an indefinite length of time, requiring no attention except the winding of the clock movement which, if so desired, may be automatically accomplished by connecting it with a master-clock, and that by severing the portion of the sheet which has passed over the anvil plate, from the roll at the termination of a determinate period of time and properly dating it, it may at any future time, be produced to provide an accurate and indisputable record of the time and day at which a signal was transmitted from a given station.

Having thus described our invention what we claim and desire to secure by Letters-Patent is:

1. In a telegraphic receiving instrument, a record sheet having a movement in one direction, a device for recording telegraphic messages upon said sheet, a relatively fixed contrivance for producing impressions upon said sheet, and a movement adapted to periodically actuate said contrivance, in successions which vary numerically in the order in which they are produced.

2. In a telegraphic receiving instrument, a record sheet having a movement in one direction, a device for recording telegraphic messages upon said sheet, a relatively fixed contrivance for producing impressions upon said sheet, and a movement adapted to periodically actuate said contrivance, in successions which vary numerically in accordance with the numbers of the hours at which they are produced.
3. In a telegraphic receiving instrument, a record sheet having a movement in one direction, a device for recording telegraphic messages upon said sheet, a relatively fixed electrical contrivance for producing impressions upon said sheet, and a movement in a circuit with said contrivance and adapted to periodically transmit successions of electric impulses to the same, which vary numerically in the order in which they are produced.
4. In a telegraphic receiving instrument, a record sheet having a movement in one direction, a device for recording telegraphic messages upon said sheet, a relatively fixed electrical contrivance for producing impressions upon said sheet, and a clock movement in a circuit with said contrivance, adapted to periodically transmit successions of electric impulses to the same, which vary numerically in accordance with the numbers of the hours at which they are produced.
5. In a telegraphic receiving instrument, a record sheet having a movement in one direction, a device for recording telegraphic messages upon the said sheet, a relatively fixed contrivance for producing impressions upon said sheet, and a clock including a striking movement connected with the said contrivance to actuate it periodically in successions numerically in accordance with the numbers of the hours of the day.
6. In a telegraphic receiving instrument, a record-sheet having a movement in one direction, a device for recording telegraphic messages upon the said sheet, a relatively fixed electrical contrivance for producing impressions upon said sheet, and a clock including a striking movement, in a circuit with said contrivance to actuate the same in correspondence with the motions of the hammer-lever included therein.
7. In a telegraphic receiving instrument, a record-sheet having a movement in one direction, a device for recording telegraphic messages upon the said sheet, an electromagnet, a member connected with the armature thereof to produce impressions upon the said sheet, a mechanism to automatically change the position of the said member relative to an impression produced upon said sheet, prior to the production of the next impression during a succession of impulses transmitted to said magnet, and a clock-movement in a circuit with said magnet to

periodically transmit thereto successions of impulses varying numerically in the order in which they are produced.

8. In a telegraphic receiving instrument, a record-sheet having a movement in one direction, a device for recording telegraphic messages upon the said sheet, an electromagnet, a member connected with the armature thereof to produce impressions upon the said sheet, a mechanism to automatically change the position of the said member relative to an impression produced upon said sheet, prior to the production of the next impression during a succession of impulses transmitted to said magnet, and a clock-movement in a circuit with said magnet to periodically transmit thereto successions of impulses varying numerically in accordance with the numbers of the hours at which they are produced.

9. In a telegraphic receiving instrument, a record-sheet having a movement in one direction, a device for recording telegraphic messages upon the said sheet, an electromagnet, a member connected with the armature thereof to produce impressions upon the said sheet, a mechanism to automatically change the position of the said member relative to an impression produced upon said sheet, prior to the production of the next impression during a succession of impulses transmitted to said magnet, and a clock including a striking movement, in a circuit with said magnet to energize the same in correspondence with the movements of the hammer lever included therein.

10. In a telegraphic receiving instrument, a record sheet having a movement in one direction, a device for recording telegraphic messages upon the said sheet, an electromagnet, a member connected with the armature thereof to produce impressions upon the said sheet, a mechanism to automatically change the position of the said member relative to an impression produced upon said sheet, prior to the production of the next impression during a succession of impulses transmitted to said magnet, a clock including a striking movement in a circuit with said magnet to energize the same periodically in successions corresponding numerically with the numbers of the hours of the day.

11. In a telegraphic receiving instrument, a record-sheet having a movement in one direction, a device for recording telegraphic messages upon the said sheet, a relatively fixed electrical contrivance for producing impressions upon said sheet, and a clock including a striking movement, in a circuit with said contrivance to actuate the same periodically in successions corresponding numerically with the numbers of the hours of the day.

12. In a telegraphic receiving instru-

- ment, two record-sheets, means for moving said sheets in unison, devices for recording telegraphic messages upon the respective sheets, relatively fixed contrivances for producing impressions upon the respective sheets, and a clock movement adapted to periodically actuate said contrivances in successions varying numerically in the order in which they are produced.
- 10 13. In a telegraphic receiving instrument, a record sheet, a device for recording telegraphic messages thereon, a clock including a time-measuring movement and a striking movement, a mechanism actuated by said time measuring movement to move said sheet, and a contrivance for producing impressions upon the sheet, connected to be actuated in accordance with the motions of the hammer lever included in said striking movement.
- 15 14. In a telegraphic receiving instrument, a record-sheet, a device for recording telegraphic messages thereon, a contrivance for producing impressions upon said sheet, a clock movement connected with said contrivance to periodically actuate the same in successions varying numerically in the order in which they are produced, and mechanism associated with the said movement for moving said sheet.
- 20 15. In a telegraphic receiving instrument, a record-sheet having a movement in one direction, a device for recording telegraphic messages upon the said sheet, an electro-magnet, a member connected with the armature thereof to produce impressions upon said sheet, a mechanism actuated by the movement of said armature, to change the position of the said member relative to an impression produced upon said sheet, prior to the production of the next impression during a succession of electric impulses transmitted to said magnet, and a clock movement in a circuit with said magnet to periodically transmit thereto successions of impulses varying numerically in the order in which they are produced.
- 25 16. The combination with a telegraphic transmitter, of a receiving instrument including an electromagnet in a circuit with said transmitter, a member associated with the armature of said magnet for producing impressions upon a suitable surface, and means actuated by the movement of said armature to change the position of the said member relative to an impression produced upon said surface, prior to the production of the next impression when a succession of impulses are transmitted to the said magnet.
- 30 17. In a telegraphic receiving instrument, a record sheet having a movement in one direction, an electro-magnet, a member associated with the armature thereof to produce impressions upon said sheet, and means actuated by the movement of said armature to move the said member after an impression is produced upon said sheet, in a direction transverse to the direction of movement of the same, and prior to the production of the next impression when a succession of impulses are transmitted to said magnet.
- 35 18. The combination with a telegraphic transmitter, of a receiving instrument including an electro-magnet in a circuit with said transmitter, a member associated with the armature of said magnet for producing impressions upon a suitable surface, and means actuated by the movement of the armature of the said magnet, to move the said member step by step by changing its position relative to each impression produced upon said surface, prior to the production of the next succeeding impression when succession of impulses are transmitted to the said magnet.

In testimony whereof we have affixed our signatures in presence of two witnesses.
